UNITED STATES PATENT OFFICE.

JULIUS C. HERRMANN, OF ST. LOUIS, MISSOURI, ASSIGNOR TO AMERICAN CAR & FOUNDRY COMPANY, OF ST. LOUIS, MISSOURI, A CORPORATION OF NEW JERSEY.

CAR CONSTRUCTION.

No. 821,490.

Specification of Letters Patent.

Patented May 22, 1906.

Application filed February 5, 1906. Serial No. 299,497.

To all whom it may concern:

Be it known that I, JULIUS C. HERRMANN, a citizen of the United States, residing at the city of St. Louis, State of Missouri, have invented a certain new and useful Improvement in Car Construction, of which the following is a full, clear, and exact description, such as will enable others skilled in the art to which it appertains to make and use the same, reference being had to the accompanying drawings, forming part of this specification, in which—

Figure 1 is a vertical sectional view through a portion of a car, illustrating my improvement; and Fig. 2 is a detail view illustrating the manner of making the stake or post used in my improved car construction.

This invention relates to a new and useful improvement in car construction, and particularly to the stake or post used to reinforce the side and end walls. Heretofore it has usually been the practice to make such stakes or posts of pressed steel, which necessitates special dies and several operations in the manufacture of the stake. Rolled angles and bars of various cross-sections have also been employed. The difficulty, however, in the use of rolled material heretofore employed is that the same cross-sectional area prevails throughout the length of the stake, which in pressed-steel construction is obviated by tapering the stake from the bottom to the top. Inside gusset-plates have also been employed, and these have been secured to the side walls of the car and extend down to the floor, to which the base-flange is riveted. The inclined edge of the stake or post may or may not be reinforced by an angle or flange.

The object of my present invention is to utilize rolled sections which are cut to the desired length, after which the web is sheared diagonally, and where it is desired to have the web extend through the floor and be riveted to the underframing of the car the flanges may also be cut away near the lower edges of the stake, or the flange may be left in position and a connecting-angle riveted to the web and to the floor, as is well understood in car construction. By shearing the

web diagonally it is obvious that I obtain a tapered stake possessing the strength incident to such a formation and in addition am enabled to get two stakes out of one piece of rolled material. While I have shown the channel-beam as the rolled member from which stakes are made, it is obvious that I-beams, Z-beams, or beams of other cross-sections may be manipulated as herein mentioned.

In the drawings I have shown a vertical sectional view through one end of a gondola car in which 1 is the side wall; 2, the end wall; 3, the floor; 4, the draft-sill; 5, the end sill, and 6 is the platform-plate.

7 is the stake, whose flange is riveted to the end wall of the car, said flange being cut away just above the floor-line, so that the web may extend beneath the floor and be riveted to the draft-sill.

In Fig. 2 I have shown a section of rolled channel-beam as it is operated upon to produce two stakes. Where the stake is used in connection with the side wall of the car, it is obvious that the web may extend through the floor and be riveted to the cross-bearers or transversely-arranged floor-supports in the same manner as said webs are riveted to the draft-sills.

Having thus described the invention, what is claimed as new, and desired to be secured by Letters Patent, is—

The combination with the wall of the car, of an underframing for supporting the floor, a stake composed of a portion of a rolled flanged member whose web is cut diagonally and whose flanged portion is riveted to the wall of the car, said flange being cut away above the floor-line, and said web portion extending beneath the floor-line and being riveted to a member of the underframing; substantially as described.

In testimony whereof I hereunto affix my signature, in the presence of two witnesses, this 2d day of February, 1906.

JULIUS C. HERRMANN
